UNITED STATES PATENT OFFICE

91,981

DESIGN FOR AN ICE CREAM CONE

David Canter, Brooklyn, N. Y.

Application January 11, 1934, Serial No. 50,374

Term of patent 14 years

To all whom it may concern:

Be it known that I, DAVID CANTER, a citizen of the United States, residing at Brooklyn, in the county of Kings and State of New York, have invented a new, original, and ornamental Design for Ice Cream Cones, of which the following is a specification, reference being had to the accompanying drawing, forming part thereof.

Fig. 1 is a view in perspective of an ice cream cone embodying my design;

Fig. 2 is a front elevation of the ice cream cone;

Fig. 3 is a side elevational view;
Fig. 4 is a top plan view; and
Fig. 5 is a bottom plan view.

I claim:

The ornamental design for an ice cream cone as shown.

In witness whereof, I hereunto subscribe my name this 6th day of January, 1934.

DAVID CANTER.
